UNITED STATES PATENT OFFICE.

HUGO PHILIP CRUSH, OF CHARLTON, ENGLAND, ASSIGNOR TO ALFRED JAMES, OF LONDON, ENGLAND.

SECTIONAL FILTER FOR EXHAUST FILTRATION.

No. 884,797.

Specification of Letters Patent.

Patented April 14, 1908.

Application filed December 17, 1906. Serial No. 348,324.

To all whom it may concern:

Be it known that I, HUGO PHILIP CRUSH, a subject of the King of Great Britain, residing at Charlton, in the county of Kent, England, have invented Improvements in Sectional Filters for Exhaust Filtration, of which the following is a specification.

The object of this invention is to facilitate the de-watering or the washing of ore slime, 10 precipitate and other material by the provision of a rigid self-cleaning or emptying filter-frame worked by the application of a vacuum as herein described. In other proposed methods of vacuum or exhaust filtration the filter-frame is cleaned by hand or by 15 a flow of water or a reverse current of air or water, all of which are expensive.

This invention provides a frame which from its construction and method of working 20 is self-emptying and requires no back pressure of air or water.

The invention is illustrated in the accompanying drawing, in which

Figure 1 is a side view of one of the filter- 25 frames mainly in section, Fig. 2 a cross section thereof drawn to a larger scale, and Fig. 3 a detailed view of part of the filter-frame drawn to a still larger scale.

I make a frame of great rigidity and of 30 great superficies and yet of but little weight by building together sheets of pressed metal such as iron, or aluminium when suitable, such metal being pressed into ridges or channels similar to corrugated galvanized iron, 35 but with the difference that the corrugations or ridges are sharp or angular and not rounded, so as to present support but not surface to the filtering material placed on them. Such ridges may be one inch or any other 40 convenient distance between the centers.

The sheets, which may be of iron 1/50th of an inch thick or other convenient size, and which may be protected from the action of the solution by special paint, galvanizing or 45 other suitable means, are attached to each other by rivets at say 4" from the bottom of each sheet until they form a plate 1 of the required size, say 14 ft. by 14 ft. This plate 1 is supported in a rectangular frame composed of a pipe 2, of 1 1/2 inch diameter or other suitable size, which runs along the ends and bottom of said plate and a top bar 3, which

runs along the top thereof, the upper ends of said pipe extending through said top bar.

The pipe 2 is slotted along its top at the bottom of the frame so as to receive the corrugated plates 1, the slots being interrupted for 1/2" every 18" or other convenient distance, as shown at 4, to serve as a support to the sides of the pipe. The top of the corrugated plate 1 is let into the top bar 3, and wires 5 which may be 6" long by 1/16" thickness are fixed at an angle from the wood block and the plate so as to prevent the filtering material 6 being drawn into the corner 60 formed by the junction of the wood and corrugated metal sheet. These wires constitute spreaders for the cloth or filtering fabric and facilitate the self-cleaning or emptying action of the plate. I prefer that these wires 70 should be fixed with a slightly convex curve as shown in Fig. 2, as it will be found that after the plate has received a suitable charge, determined by experiment for each type of material, so soon as the application of the 75 vacuum ceases the cloth and material will fall away from the junction of the wire to the vertical sheet of the frame, and this falling away causes a rolling or falling action to start on the material on the frame, which thus 80 empties itself.

The corrugated sheet 1 is fixed within the frame composed of the block or rail 3 on top and the tubes 2 along the ends and bottom by bolt 7 of iron or other suitable material 85 placed alternately each side of the iron sheet (four 1/8" bolts would suffice for the size sheet above mentioned); the lower ends of the bolts are riveted flush into the bottom tube thus presenting a smooth surface for the filtering material.

Along the four vertical sides of the rail 3 which is preferably composed of wood is chased a groove 8 which may be 3/8" wide and deep to permit of the calking in of the edges 95 of a bag 6 of suitable filtering fabric, sewed to shape, in which the frame constructed as before described is placed; the edges of the bag are calked with twine, thin rope, or other suitable material, and on each of the four 100 vertical sides of the rail 3 is screwed a suitable piece of timber 9 of similar surface dimensions and say 1" thick, which keeps tight the joint of the top of the bag with the

wooden rail. Provision is also made for the escape of air when immersing the frame, by inserting a piece of pipe 10 through the frame to near the surface of the corrugated plate; 5 this air escape tube is connected by hose 11 or other suitable means to the escape air pipe system 12 as described below.

To the top of the wooden rail at suitable places are fixed two sets of bolts 13 each with 10 a top plate 14 by means of which the frame can be swung on the two joists 15 forming the main support of the group of frames termed a basket. A suitable number of these filters or frames having the filtering 15 bags or fabric thereon, which may be for instance twelve, are swung on to two suitable joists, which may for example be steel joists of 8" by 3" section, at suitable intervals or distances, say 12", apart, so that the frames 20 may be in parallel at intervals sufficient to allow the cakes to fall off readily.

The two joists 15 each carry a main pipe to one (16) of which the suction pipe 2 of each plate is connected by hose 17 or other suitable 25 means, and it is convenient to have gage glasses 18 connected at each point so that the precise working of each frame may be ascertained and kept under observation; to the other main pipe 12 the air escape attachment 30 is made from each frame, and this main has a cock by which connection with the atmosphere can be made or cut off. The vacuum main 16 is connected to the vacuum pump system by means of flexible hose or other 35 suitable means. The two joists 15 are also provided with four rings or hooks 19 one at the end of each joist, by means of which the whole set of frames or basket may be swung and raised or lowered or suspended at will. 40 The method of working is to immerse the basket filter into a suitable tank containing, in suspension, the material to be filtered, or dehydrated; such a tank may for instance be one foot larger each way than the basket 45 frame and may be provided with guides on opposite sides of the upper edge of the tank to direct its basket as it is lowered and to keep it in position.

The material to be filtered may be kept in 50 suspension by suitable known means. The pipes may be conveniently jointed to facilitate removal in the event of any choking occurring.

As the basket is being lowered into the agitated pulp, the escape air cocks are opened until the basket is in position and air ceases to escape; the escape cocks are now turned off and the vacuum turned on. The behavior of each frame and the amount of solution 55 and of air being drawn through may be readily ascertained by glancing at the gage glass indications after a suitable interval to be determined by experiment; thus a very

clayey slime containing but little fine sand perceptible to the touch takes 45 minutes 65 with a vacuum of 25 inches to form a suitable cake 1 $\frac{1}{4}$ to 1 $\frac{1}{2}$ inches thick; the basket is lifted with the vacuum still on and plunged into a similar tank containing water or other washing fluid (if the material is to be washed 70 instead of dehydrated) and the water or other fluid is sucked through for a sufficient time—in the above instance from 30 to 40 minutes. The basket is then again lifted with the vacuum still on and hoisted to the 75 discharging trough. So soon as cracks appear on the surface of the dehydrated material the vacuum is turned off and the air escape cocks turned on; the cloth 6, released from the effect of the vacuum, bellies, and 80 the cakes if properly made fall off with a rolling motion. If necessary the falling off of the cakes can be assisted by a man with a stick. The edges of the framing are wiped down and the basket is now ready for a fresh 85 charge.

What I claim, and desire to secure by Letters Patent, is:—

1. A filter section comprising a light rigid filter frame composed of a thin ridged metal 90 plate and a marginal frame consisting of a top bar and a tube adapted for connection with a vacuum apparatus, said tube extending along the ends and bottom of said plate and being provided with an exhaust opening, and a filter bag disposed on said frame and calked into the top bar thereof.

2. A filter section comprising a light rigid filter frame composed of a thin ridged metal plate and a marginal frame consisting of a 100 top bar and a tube adapted for connection with a vacuum apparatus, said tube extending along the ends and bottom of said plate and being provided with an exhaust opening, and a filter bag disposed on said frame and 105 inclined spreaders dependent from said top bar on opposite side of said plate to facilitate on the stoppage of the exhaust automatic breaking away of the cake formed on the filter fabric during the application of a 110 vacuum.

3. A filter frame adapted for carrying a filtering fabric on opposite sides for exhaust filtration, comprising a sheet metal plate having angular ridges, a marginal frame therefor 115 and spreaders extending downward from the top bar of said frame on opposite sides of said plate for spreading the filter fabric near the top.

4. A filter frame adapted to carry a filtering fabric on opposite sides for exhaust filtration, comprising a corrugated sheet metal plate and a marginal frame therefor, the bottom of said frame being a slotted exhaust pipe and said corrugated plate extending 125 into the slot thereof.

5. A filter frame adapted to carry a filtering fabric on its opposite sides for exhaust filtration, comprising a sheet metal plate having angular corrugations and a marginal frame therefor, the bottom of said frame being a slotted exhaust pipe and said corrugated plate extending into the slot thereof.

In testimony whereof I have signed my name to this specification in the presence of two subscribing witnesses.

HUGO PHILIP CRUSH.
